UNITED STATES PATENT OFFICE

141,199

DESIGN FOR A COMBINED LIPSTICK CASE AND SHADE INDICATOR

Arthur Basescu, Brooklyn, N. Y.

Application March 25, 1944, Serial No. 113,041

Term of patent 7 years

(Cl. D86—10)

To all whom it may concern:

Be it known that I, Arthur Basescu, a citizen of the United States, residing at Brooklyn, in the county of Kings and State of New York, have invented a new, original, and ornamental Design for a Combined Lipstick Case and Shade Indicator, of which the following is a specification, reference being had to the accompanying drawing forming a part thereof.

I claim:

The ornamental design for a combined lipstick case and shade indicator, substantially as shown.

ARTHUR BASESCU.
